PARKING METER

Joseph F. Balisteri, Dallas, Tex.

Application May 20, 1938, Serial No. 208,987

2 Claims. (Cl. 161—15)

This invention relates to parking meters and more particularly to meters employed by municipalities for controlling and predetermining the parking time of vehicles on city streets as a means of collecting revenue.

The principal object of the invention is to provide a novel clock-actuated, coin and weight-controlled mechanism wherein provision is made for return of the time indicating pointers to their original positions through the medium of 10 cooperating devices rendered operative by the insertion of a coin.

Another object of the invention is to provide a housing carrying two oppositely directed and numerically graduated faces over which pairs of oppositely directed pointers are moved and which faces are also provided with indicia by which the parking time, over a predetermined period 15 may be accurately ascertained.

The expressed objects being foremost, other and lesser objects as well as certain salient features of construction will become manifest in the course of the following description, taken with the accompanying drawing, wherein:

Figure 1 is a front elevational view of a parking meter constructed according to the present invention with portions broken away.

Figure 2 is a similar view in elevation, broken away to show certain of the interior parts.

Figure 3 is an elevational view in vertical section showing the clock mechanism, cable and pulley for raising the pointers and the weight for returning the pointers to starting position.

Figure 4 is a view on line 4—4 on Figure 2, fragmentarily showing the coin release elements.

Figure 5 is a fragmentary elevational view of the lower part of Figure 4.

Figure 6 is a transverse section on line 6—6 on Figure 3.

Figure 7 is a side elevational view of the clock mechanism housing, showing the clutch means in cross-section taken on line 7—7 on Figure 3, and

Figure 8 is a perspective view showing the coin chute fragmentarily, the counter-balanced coin actuated arm and the clutch control lever operated thereby.

Continuing with a more detailed description of the drawing, the housing 1 is adapted to be mounted upon a post or pedestal, not shown, at spaced intervals along a street or thoroughfare, properly zoned. This housing contains the clock-controlled mechanism, aided in its operation by a weight and a coin. The housing encloses two

faces A in opposed relationship, bearing numerals from zero to 60 downward from a transverse line designated "over-time." Above this line are numerals from 5 to 10 (or more) upward, indicating in minutes the "over-time" parking above a period fixed by the numerals below the line.

A horizontal rod 2 extends through vertical slots 3 in the faces A and carries upon either end pointers 4, directed oppositely toward the vertical rows of numerals indicating time in minutes.

The clock mechanism is generally indicated by the reference numeral 5 in Figure 3, and upon the shaft 3^a driven thereby is mounted a peripherally grooved pulley 6. Connected at one end to this pulley is a cable 7 which extends upwardly and over a second grooved pulley 8, in the top of housing 1 and has a weight 9 suspended from its opposite end.

It is apparent from the foregoing that while the clock mechanism is operating, the pulley 6 will be rotated in the direction of the arrow in Figure 3, through a clutch to be presently described, and the cable 7 will be wound thereon, causing the weight 9 to be elevated in a tubular guide 9^a connected to a plate 9^b, secured to and directed outwardly from the inner wall of housing 1. Thus, the shaft 2 and pointers 4 will move upward, the pointers indicating the diminishing time periods on faces A.

It is necessary to limit the rotative travel of the pulley 6 to determine the upward travel of the pointers 4. This is accomplished through the medium of a detent or lever 10, pivoted at 11 to one wall of the housing 12 which contains the clock mechanism 5. One end of this lever is directed into the space between the housing 12 and pulley 6 and in the path of a pin 14 which is mounted on the pulley 6 and therefore travels therewith. It may be mentioned here that the pin 14 is intended to be adjustable, that is to say, movable to other locations around the pulley relative to the point of securing thereto of the end of cable 7 so that the length of cable unwound from the pulley may be predetermined. When the pin 14 strikes the end 13 of the lever 10, the opposite end of the latter will come to rest against the periphery of the housing 12 and the pulley 6 will therefore be restrained against further rotation until such time as a coin or token is dropped into the coin chute 15.

When a coin 15^a (Figure 1) is inserted in chute 15, it falls against the inwardly turned

lower end 15^b of a depending arm 16, the latter being pivoted at its upper end to the rear wall of coin chute 15 and provided with a counter-balancing weight 17 which normally urges the lower end of arm 16 into the slot in the coin chute in the path of a coin passing downwardly therein.

It will be noted in Figures 4 and 5 that a highly flexible strip 17^a is secured at a to the rear wall of the coin chute and has an inwardly turned lip 16^a on its lower extremity which enters an aperture in the chute wall immediately below the slot therein which accommodates the end 15^b of arm 16. Above this lip is a protuberance 17^b struck outwardly from strip 17^a and underlying the end 15^b of arm 16. The purpose of this arrangement is to intercept a coin by the lip 16^a after it passes the end 15^b of arm 16, in the manner shown in Figure 1 until such time as another coin is inserted in the chute, whereupon the latter coin, in striking 15^b will cause the arm 16 to urge the protuberance 17^b outward, flexing the member 17^a causing 16^a to retract to release the supported coin, and to return to its position in the aperture in time to intercept the second coin. The intercepted coin is visible through an opening (not shown) in the housing 1.

It is understood that in order that the clock mechanism may operate the cable as described, the clutch elements must be in engagement. However, when it is desired to return the pointers to the starting position or bottom of the faces A, the clutch elements must be disengaged. This is accomplished by an arm or lever B, (Figures 2 and 8) having a lateral extension 18 which bears against arm 16 near its upper end. A yoke 18^a supports the arm B and is pivotally mounted by means of pins a' journaled in ears carried by a plate b' mounted on the housing 12 and which yoke engages a clutch element 19. When a coin, in passing downward in chute 15, strikes the end 15^b of arm 16 to urge the latter outward simultaneously, the arm B is actuated to move the yoke 18^a and consequently the clutch element 19 outwardly against the resistance of spring 20, which latter normally holds the clutch elements in frictional engagement. While the action is instantaneous, sufficient time is permitted for the weight 9 to drop to the bottom of its tubular guide 9^a, bringing with it the pointers 4, since the pulley 6 is free to rotate and unwind the cable 7.

It is to be understood that when the pointers reach the upper limit of travel the clutch faces will slip to prevent any damage to the parts. The pointers will not drop until a coin is deposited into the chute 15. At this time, the clock starts functioning to begin raising the pointers to register parking time consumed and remaining.

In operation, a coin is inserted into the chute 15 which strikes the end 15^b of arm 16, whereupon arm B is moved to effect release of the clutch elements 19. The pointers 4 then drop, indicating the period of parking time allotted. Should the time allotted for a zone be less than the full measure of time on the faces A, the pin 14 is accordingly moved to a position to shorten the length of cable which might be unwound from pulley 6. The pointers 4 would then descend only to the limit allowed by the cable, or at some predetermined point intermediate the tops and bottoms of faces A.

When the clock requires rewinding, a key 21 is used but is, of course, removed when the spring of the mechanism is wound.

Manifestly, the construction as shown and described is capable of some modification and such modification as may be construed to fall within the scope and meaning of the appended claims is also considered to be within the spirit and intent of the invention.

What is claimed is:

1. A parking meter including a housing having open sides, vertically slotted and numerically scaled faces in said openings, a rod having its ends protruding through said slots and carrying pairs of oppositely directed pointers, a weight connected intermediate the ends of said rod, a clock mechanism, a pulley operated by said clock mechanism, a clutch effecting connection between said pulley and clock mechanism, a cable connected to said pulley, a second pulley in the top of said housing, said cable overriding said second pulley and being joined to said weight to support the same, whereby said pointers will ascend from an initial position when said clutch is operative, and coin controlled means operative to release said clutch to cause said weight and pointers to drop to their initial position in said housing.

2. A parking meter comprising a housing having oppositely directed, vertically slotted and numerically scaled faces, a rod extending through said slots carrying a pointer on either end for movement over said faces, a clock mechanism, a pulley operated by said clock mechanism, clutch elements mounted on the shaft of said pulley and having spring means to effect engagement between said pulley and clock mechanism, a cable connected to said pulley, an idler pulley in the top of said housing over which said cable passes, the latter being connected to said rod whereby to raise said rod and pointers when said clutch elements are engaged, a weight also carried by said rod and coin controlled means operative to actuate said clutch elements whereby to release said cable to the action of said weight to lower said pointers.

JOSEPH F. BALISTERI.
